US00D935504S

(12) **United States Design Patent** (10) **Patent No.:** **US D935,504 S**
(45) **Date of Patent:** **** Nov. 9, 2021**

(54) **TAIL OF A ROBOT**

(71) Applicant: **SONY CORPORATION**, Tokyo (JP)

(72) Inventors: **Noriaki Takagi**, Kanagawa (JP);
Hidenori Ishibashi, Tokyo (JP); **Yohei**
Watanabe, Aichi (JP); **Takayuki Ito**,
Kanagawa (JP)

(73) Assignee: **SONY CORPORATION**, Tokyo (JP)

(**) Term: **15 Years**

(21) Appl. No.: **29/765,020**

(22) Filed: **Jan. 5, 2021**

Related U.S. Application Data

(63) Continuation of application No. 29/645,961, filed on
Apr. 30, 2018, now Pat. No. Des. 916,160.

(57) **CLAIM**

The ornamental design for a tail of a robot, as shown and described.

DESCRIPTION

FIG. 1 is a front, top, right perspective view of a tail of a robot showing our new design;

FIG. 2 is a front, bottom, left perspective view thereof;

FIG. 3 is a rear, top, left perspective view thereof;

FIG. 4 is a rear, bottom, right perspective view thereof;

FIG. 5 is a front elevational view thereof;

FIG. 6 is a rear elevational view thereof;

FIG. 7 is a left side elevational view thereof, a right side elevational view thereof being a mirror image;

(Continued)

FIG. 8 is a top plan view thereof; and,
 FIG. 9 is a bottom plan view thereof.
 The broken lines depict portions of the tail of a robot that
 form no part of the claimed design.

1 Claim, 9 Drawing Sheets
